POLISHING APPARATUS

Walter Geduhn, Berlin-Steglitz, and Ludwig Petty, Berlin, Germany; vested in the Alien Property Custodian

Application March 16, 1939, Serial No. 262,262
In Germany August 21, 1937

2 Claims. (Cl. 91—37)

This invention relates to an apparatus for waxing and polishing surfaces of any kind and has particular reference to a floor polisher.

It is an object of the invention to avoid the drawbacks and inconveniences caused with the existing apparatus of the kind referred to in which the wax is applied to the floor in a dissolved form, allowed to dry for several hours and then polished.

Another object of the invention is to provide means for polishing any surfaces quickly and efficiently, with small labour and cost and simple apparatus.

With these and other objects in view, as may become apparent from the within disclosures, the invention consists not only in the structures herein pointed out and illustrated by the drawings, but includes further structures coming within the scope of what hereinafter may be claimed.

The character of the invention, however, may be best understood by reference to certain of its structural forms, as illustrated by the accompanying drawings in which—

Fig. 1 is a diagrammatic view of an apparatus for use as a floor polisher, having the invention applied thereto.

Fig. 2 is a longitudinal section of Fig. 1.

Fig. 3 is a horizontal section through the same apparatus, on the brush motor axis.

Figs. 4 and 5 are details of the device for holding the wax block, in a longitudinal section and in a front view, respectively.

Fig. 6 is a section of a modification, on line VI—VI of Fig. 8.

Fig. 7 is a section on line VII—VII of Fig. 8.

Fig. 8 is a plan view of the modification shown in Figs. 6 and 7.

Similar reference numerals denote similar parts in the different views.

Referring now to the drawings in greater detail, and first to Figs. 1 to 5, it will be seen that brush rollers 2, 2', 2'' are mounted for rotation in a main frame 1 of the machine. Roller wheels 3, 3' are also mounted for rotation and vertical sliding in the frame 1, as indicated in dotted lines, and adapted to be lifted by a cam device 5 operated by rotation of a cam 5' on a hand lever 4 which to this end can be rotated and advantageously can be telescopically elongated and shortened, whereby the brush rollers can be engaged with and disengaged from the surface 6 to be polished. A block 8 of hard wax is disposed in a holder 7 in the frame 1 and consists of a wax which does not contain any solvents or other

ingredients for rendering it more plastic or pasty. I provide the said block 8 in an inclined position in the frame and with respect to the roller 2', in such a manner that its end surface 9 engages the brush roller 2' at a point below a horizontal plane passing through the roller axis, whereby the distance from said wax surface to the floor is very short. Rollers 9 may be provided to render the wax block easily movable in its holder and steel wires 10 or the like (Figs. 4 and 5) may be provided on the front end of the holder, between the brush and the wax block and in the direction of motion of the brush, in order to prevent too intensive attraction and action of the brush roller upon the wax block, without hampering the work of the brush. In order to further prevent too high wearing and consumption of the wax, the holder may be in the form of a yielding cage.

20 The brush roller 2' is completely enclosed in the casing 11, with the only exception of the lower aperture towards the floor and a ring of closure brushes 13 is provided underneath the casing 11, whereby loss of wax is prevented. 25 Moreover the brushes 13 serve to clean and polish the surfaces to be waxed. The brushes are driven by an electric motor indicated at 14 in Fig. 3. The exhausting and cooling fan 15 which is normally present in high speed motors is preferably so designed that it may be used as a vacuum cleaner. To this end, it is disposed in a separate chamber 16 having adjustable apertures 17 for the motor cooling. A further aperture or 30 valve 18 serves for producing the stream of suction air for the vacuum cleaning action. Moreover, auxiliary devices for room cleaning may be connected at 19.

35 A preferred practical embodiment of our novel floor polisher is shown in Figs. 6 to 8. Only a single brush roller 20 for applying and polishing the wax is provided in this case in a casing 26 and driven from a motor 21 through a shaft 22 and worm gear 23. Mounted on the shaft 22 is a blower or fan wheel 24 which through the channel 25 effects the exhaust of dust. The apparatus is moved in the direction of the arrow, i. e., with the mouth piece of the channel 25 in front of the brush roller so that the vacuum cleaning action precedes the brushing action. A ring of closure brushes 27 surrounds the brush roller and suction inlet.

40 The wax block 37 is disposed in a casing or holder 28 on both sides of the motor casing 29, Fig. 8, and introduced through a slot 30 from the rear side. A rod 32 passes through a lug 31 of

the casing 28 and is operated by a bowden control 33, the opposite end 34 of which is actuated by a lever 35 secured to a handle 36. It will thus be understood that the wax block 37 can be resiliently or yieldingly moved or withdrawn in its holder or with the same to stop the wax supply if desired. The lower end of the handle 36 is provided with a bifurcated portion 38 pivoted to the motor casing 29 at 39, 39'. The exhaust pipe of the vacuum cleaner or cooling fan is shown at 40.

It will be seen that also in this apparatus the wax block 27 is positioned at an acute angle with respect to the floor, with its active surfaces below the horizontal plane passing through the brush axis.

Wherever in the specification and claims "hard wax" is mentioned, it is intended to define a 100% wax composition, and not a mixture of wax and dissolving oils containing perhaps only 50% wax. Particles of such hard wax, detached from a solid block of the wax in a brushing operation, are softened somewhat to a plastic state in which they may be effectively applied to a surface to be polished due to heat resulting from friction between the block of wax and the brush by which the particles are detached from the block of wax. Where solvents are used, the softer wax mixture applied to a surface must be allowed to dry before polishing, whereas the hard wax applied in accordance with this invention may be and is polished immediately upon application.

It will thus be understood that a hard wax which is free from solvents or other admixtures of this kind will be rubbed into the floor surfaces in the form of a wax dust which in view of the frictional heat developed as it is scraped off from the block is still warm and plastic. The brushes are not smeared and therefore, are adapted immediately to rub the wax that has been scraped off from the block into the surfaces to be polished. Also, the wax is not scattered around, due to the perfect enclosure of the brush roller and the provision of the closure brushes 21, 45 Fig. 7.

Compared to the known processes our novel apparatus offers the advantage that the wax layer can be applied on the surface to be treated and dry-polished in one operation without soiling of the brushes or bad smell as caused by the use of solvents. Also, the fire danger so far produced by the solvents in the wax is eliminated by our invention.

It is also contemplated that one or more disc shaped brushes may be used in our novel floor polisher instead of a roller shaped brush as shown.

We are aware that many further changes may be made and numerous details of construction may be varied through a wide range without departing from the principles of this invention, and we, therefore, do not purpose limiting the patent granted hereon otherwise than is necessitated by the prior art.

We claim:

1. In a polishing apparatus, in combination, a main frame, a rotary brush, means for rotating said brush and means including rollers for holding a block of hard wax in said frame in an acute angle with respect to the surface to be polished, with its front surface engaging said brush at a point below a horizontal plane passing through the brush axis, whereby a short travelling distance is obtained for the wax scraped off from the block by said brush and applied on the surface to be polished.

2. In a polishing apparatus, in combination, a main frame, a rotary brush, means for rotating said brush and means including a grate member for holding a block of hard wax in said frame in an acute angle with respect to the surface to be polished, with its front surface engaging said brush at a point below a horizontal plane passing through the brush axis, whereby a short travelling distance is obtained for the wax scraped off from the block by said brush through said grate member and applied on the surface to be polished.

WALTER GEDUHN.
LUDWIG PETRY.
